MATERIAL EDGESTITCHER GUIDE MECHANISM FOR USE WITH THE PRESSER FOOT OF SEWING MACHINES

Paul C. Wiegandt, Brooklyn, N. Y.; Katherine Wiegandt administratrix of said Paul C. Wiegandt, deceased

Application September 3, 1948, Serial No. 47,704

4 Claims. (Cl. 112—153)

The invention relates to sewing machine attachments, more especially to a guide member adapted for use with the customary reciprocable presser foot thereof, said guide member being designed to guide the edges of superposed material such as cloth, in sewing a seam close to said edges. I am aware that such guide members in association with presser members have heretofore been proposed, but the effective or toe portion thereof in these constructions continue to reciprocate along with the presser foot block and its actuating rod. Such an arrangement is not entirely satisfactory, particularly when stitching along edges of irregular perimeter such as angular and arcuate portions.

It is an object of the present invention to provide a novel presser foot-guide member combination wherein the toe portion of the guide member does not follow the reciprocating motion of the presser foot rod but continues to maintain contact at its lower edge with the top surface of the sewing machine table over which the goods are advanced for stitching.

A further object of the invention is to provide means whereby the guide member toe may be manually withdrawn from its contact with the table top and locked to the presser member in displaced relationship to said top throughout the stitching operation when it is desired to effect ordinary sewing operations with the machine.

A still further object is to provide a guide member affording a means for continuous contact of goods edgewise therewith to prevent slipping of the goods past the guide toe or overlapping of the edge portions of said goods irrespective of irregularities in the boundary of the edge portions being stitched.

Another object of the invention is to provide guide mechanism which may be combined readily with standard forms of presser foot members as utilized in both domestic and commercial types of sewing machines.

Still another object of the invention is to provide a presser foot member-guide member combination which is simple to apply to a sewing machine, simple to operate and through the use of which work may be accomplished considerably faster than heretofore and better results obtained, particularly in relation to power-operated sewing machines; also admitting of sewing closer to the edges than is generally possible in edgestitching as heretofore conducted.

In carrying out the invention, the guide member is in the nature of a slide element slidably mounted over ways provided at one side of the customary presser member, said slide element

2

terminating at the bottom in a thin blade or toe element extending between the tines of the bifurcated foot element of the presser member, the lower edge of said toe element being normally extended below the tines to contact with the table top or intermediate material upon a sewing machine and maintaining this contact irrespective of the reciprocations of the presser foot rod. This is accomplished by a spring retained in the presser member acting on a member extending from the slide element; and provision is made to lock said slide, when desired, in an elevated position with the lower edge of the toe maintained substantially flush with the bottom of the tines of the presser foot element.

The nature of the invention, however, will best be understood when described in connection with the accompanying drawings, in which:

Fig. 1 is a fragmentary view in perspective illustrating the use of the novel guide member as associated with customary presser foot member.

Fig. 2 is a horizontal section thereof with the needle and needle bar removed.

Fig. 3 is a side elevation of the novel guide member-presser foot member combination with the toe of the guide member indicated in the retracted position by broken lines; and Fig. 4 is an end view.

Fig. 5 is a bottom view of the novel combination.

Fig. 6 is an elevation of the novel combination at the side of the presser foot member to which the guide member is applied.

Fig. 7 is a transverse section taken on the line 7—7, Fig. 6 of the drawings, and looking in the direction of the arrows.

Fig. 8 is a similar section taken on the line 8—8, Fig. 6 of the drawings.

Fig. 9 is a fragmentary view in perspective of the slide element of the guide member.

Fig. 10 is a horizontal section taken on the line 10—10, Fig. 8 of the drawings, and looking in the direction of the arrows.

Fig. 11 is a front elevation of the slide element of the guide member.

Referring to the drawings, 20 designates the top of a sewing table or commercial sewing machine designed to receive the goods or material 21, the overlying edges 22 and 23 of which are to be stitched as close to the edge as possible by the needle 24 actuated by needle bar 25 in the usual manner. This needle operates in the slot 26 which is formed between the tines 27 and 28 of the reciprocable presser foot member 29 through the action of the actuating rod 30.

The member 29 may be attached to this rod in

the customary manner through screw 31 passing through open-ended slot 32 of the member. At its lower end member 29 pivotally carries the spring-urged presser foot element 33 comprising the tines 27 and 28—all of which is well understood and forms no particular part of the present invention.

In accordance with the invention, however, the presser member 29 has associated therewith a guide member comprising a slide element 35 with top lip or finger piece 36 and lower blade or toe portion 37. The latter has a generally straight edge 38 (Figs. 3, 5 and 6) along the bottom which is designed to rest normally upon the top 20 under a predetermined spring pressure and immediately adjacent the juxtaposed customary cloth advancing means or feed dogs 37'. The slide member to this end is provided with inturned sides 39 and 40 respectively, fitting about ways 41 and 42 provided by the one side 43 of the presser member. Also, the body of the latter is provided with a longitudinal bore 45 with adjacent communicating lateral slot 46 through which passes a screw 47 threaded in the boss 48 of the slide element, said screw extending into the bore 45. A coiled spring 49 mounted in the bore 45 contacts through its one end the said screw 47 and at the other and outer end the spring is engaged by a screw plug 50 threaded into the bore. Being thus confined between the screw 47 and plug 50, the tension on the spring, and consequently on the slide element, may be regulated. This determines as well as maintains the contact pressure exerted by the toe 37, its downward movement, however, being limited by the bottom of the slot 46. The toe 37 is provided with a lateral reinforcing rib 51 which extends into a slot 52 (Fig. 5) of the tine 28 and beyond the same substantially to the bottom of the ways 42. As shown, said toe 37 extends between the two tines 27 and 28, being juxtaposed to the latter; and in normal operation extends below the bottom of said tines to contact the table top, as hereinbefore described, under a predetermined pressure.

However, if desired, the toe may be placed out of action for guiding purposes by drawing the slide upwardly through appropriate manual action upon the finger piece 36 thereof and then locking it in this position so that the combination of presser member and guide member may function merely as the customary presser foot member for ordinary sewing operations. In order to retain this slide element with the toe 37 in its elevated position, one of the inturned sides of the slide element, as the side 40, is cut away longitudinally to provide a shoulder or abutment 53 and a pin 54 threaded in the body of the presser member is designed to extend transversely therethrough into the path of movement of said slide member, more especially to position under the shoulder 53, as is more clearly indicated in Figs. 8 and 10. This holds the toe with its lower edge 38 substantially flush with the bottom of the tines, as indicated in the broken-line position, Fig. 3 of the drawings.

In the use of the novel guide mechanism, it is possible to work as closely as one-sixteenth of an inch from the edges of cloth or like material; and the thickness of the same sewed together may equal or exceed slightly the amount of the toe projecting, for example, one-eighth of an inch.

Moreover, the resilient mounting of said guide member, with provision for adjustment of the tension of the spring, allows of feeding the materials forward in the customary manner through the sewing machine, as by the means 37', the toe automatically yielding to accommodate irregularities in thickness.

I claim:

1. In a sewing machine: the combination with the reciprocable bifurcated foot element of the reciprocable presser member thereof; of an associated guide member for material passing through the sewing machine, slidably mounted along a side of the body of the presser member for relative longitudinal movement and having an integral flat toe element extending between the tines of the bifurcated foot element of the presser member for free relative movement vertically in both directions and adapted to project for seam sewing operation below the bottom thereof, and resilient means normally urging the guide member with said toe element in a direction to position the lower edge of the latter below said tines to hold it non-reciprocally and constantly to the sewing machine table top during such operation of said machine, together with means to limit the extent of said relative movement of the guide member.

2. A presser foot combination for sewing machines according to claim 1, wherein the toe element of the guide member is provided with a reinforcing rib guided in a slot of one of the tines of the bifurcated foot element.

3. A sewing machine foot comprising a mounting portion, a shank connected to said mounting portion, a tread, means to attach said tread to said shank for rotation about a horizontal axis, means to bias the rear edge of the tread downwardly and an edge stitching gauge including a guide, means to mount said guide on said foot for vertical movement, means to bias said guide downwardly and means to selectively maintain the guide in raised position against the action of said last-named means.

4. A sewing machine foot comprising a mounting portion, a shank connected to said mounting portion, a tread, means to attach said tread to said shank for rotation about a horizontal axis, and an edge stitching gauge including a guide, means to mount said guide on said foot for vertical movement, means to bias said guide downwardly and means to selectively maintain the guide in raised position against the action of said last-named means.

PAUL C. WIEGANDT.
